UNITED STATES PATENT OFFICE.

EUGENE CHARLES BAECK, OF NEW YORK, N. Y.

DESIGN FOR WALL-PAPER.

45,698.

Specification for Design.

Patented May 5, 1914.

Application filed December 29, 1913. Serial No. 809,423. Term of patent 14 years.

To all whom it may concern:

Be it known that I, EUGENE CHARLES BAECK, a citizen of the United States, residing at the city of New York, borough of Brooklyn, in the county of Kings and State of New York, have invented a new, original, and ornamental Design for Wall-Paper, of which the following is a specification, reference being had to the accompanying drawing, forming part thereof.

The figure is a face view of a section of wall paper, showing my new design.

I claim:

The ornamental design for wall paper, as shown.

EUGENE CHARLES BAECK.

Witnesses:

GEO. L. BEELER,
PHILIP D. ROLLHAUS.
